SEAMLESS KNIT AMBIDEXTROUS GLOVE
AND METHOD OF MAKING THE SAME

Albert C. Ackerman, Ballston Spa, N. Y.

Application June 7, 1945; Serial No. 598,011

6 Claims. (Cl. 66—174)

1

The invention described herein, if patented, may be manufactured and used by or for the Government for governmental purposes, without the payment to me of any royalty thereon.

My invention relates to a seamless knit ambidextrous glove particularly designed as an insert or liner for an outer leather glove.

A specific object of my invention is to provide a knitted glove which may be used as a liner for an outer leather glove shell or which may be used independently as a glove itself, and which is seamless, smooth fitting, and comfortable, and which fits either hand with equal facility.

An object of my invention is to provide an ambidextrous glove, the body of which may be knit upon an ordinary circular knitting machine, knitting from the wrist up without expensive modifications of the machine.

It is a further object of my invention to provide a knitted glove which is simple, durable, and inexpensive in construction as well as convenient, serviceable, and efficient in use.

The glove is of a seamless knit pattern of ambidextrous design which will fit on either hand with equal facility and due to its particular shape and construction, will properly fit either hand as contrasted to prior art ambidextrous gloves which would fit neither hand but could be used to cover either. In the past it has been well known to use so-called ambidextrous gloves. These were usually of leather or non-elastic fabric and were not successful nor commercially useful because they were so bulky and uncomfortable as to be of no value.

The advantages of an ambidextrous glove are obvious. It avoids confusion and permits the wearer to put either glove on either hand without fumbling and without identification—which is particularly advantageous for military operations under blackout conditions. It simplifies the problem of supply and permits ready replacement of a missing glove without rendering the remaining glove useless. It prolongs the useful life of the glove, as wear is evenly distributed over both sides of the glove rather than concentrated on one face as in conventional gloves. My glove is warm, form-fitting and seamless and fits so comfortably on either hand without undue stretching or slack that until the user becomes thoroughly familiar with the gloves, he is disinclined to believe that the glove can possibly fit on the other hand because it fits so well on the one. By the specific knitting pattern of my invention, results are secured which have been long desired and sought but which have been considered by experts in the field to be unobtainable.

With the foregoing and other objects in view which will appear as the description proceeds, the invention resides in the construction as hereinbefore described and claimed; it being under-

2

stood that various changes in form, proportions and unessential detail may be made within the scope of the claims without departing from the spirit or sacrificing any advantages of the invention. For a complete description of the invention, a detailed description thereof will now be given in connection with the drawings forming a part of this specification.

Figure 1 is an edge view of part of a glove showing the symmetrical character of the design.

Figure 2 is a face view of a partially knit glove showing the first finger in place, and the pull string for the insertion of the thumb.

Figure 3 is a detail of the knit construction showing the location of a pull string for the insertion of the thumb.

Figure 4 is a diagrammatic sketch showing the picked-up stitches for the insertion of the thumb.

Figure 5 is a front elevational view of an ambidextrous glove in accordance with my invention; and

Figure 6 is an enlarged detailed perspective view of a part of the glove illustrated in the preceding figure, showing structural details of the juncture between palm and fingers.

The cuff and hand are knitted on a circular glove knitting machine starting at the wrist with the rib construction desired for the cuff, changing to a plain stitch for the palm and knitting up to the level of the base of the thumb. An opening for the thumb is provided by stitching in a false thread at an equal distance on each side of the center line so that the thumb when inserted will have the center of the thumb in line with the edge of the hand. This may be done by hand. The knitting is then continued to the base of the fingers. The glove blank is then taken off the circular knitting machine.

The fingers are not overlapped but are knit on perfectly straight on a conventional flat bed knitting machine such as the Lamb flat bed knitting machine which utilizes parallel rows of needles and which was the subject matter of U. S. Pat. No. 39,934, September 15, 1863, or other flat bed knitting machines well known to the trade. The required number of needles for the first finger are set up on the machine, the first open stitch on base 4 being picked on to the first needle on each side of the machine, and so on straight across. Enough needles are employed to knit the front 5, sides 6, and back 7 of the finger; the number of needles used exceeds the number of open stitches picked on the needles, and additional wales are thus knit at the sides of the finger. The finger is then knitted to the required length. Figure 2 shows the first finger stitched on, and loops for the picking on of the other fingers.

The first stitch for the second finger is picked on to the fourth needle on each side and the bal-

ance of the stitches picked on straight across. The three empty needles on each side are picked up the side of the first finger, in the last knitted wale, so as to join the first and second fingers together at 8 (see Fig. 6) and avoid leaving a gap between the fingers. The same procedure is followed for the other two fingers.

The thumb is stitched in by pulling the inserted thread and picking all of the open stitches 9 onto a knitting machine, a conventional flat bed machine being suitable. Eight additional needles 10, 11, 12, 13, 14, 15, 16, and 17 are set into wales of palm A adjacent that portion of the courses opened up by withdrawal of thread 1 (see Figs. 3 and 4). Thus, where the stitches 9, opened up by withdrawal of thread 1, number twelve in each course, thirty-two needles are employed: Twelve needles in the open stitches of the upper course, twelve in the open stitches of the lower course, and eight in the wales adjacent the open portion adjacent either end of the open portions thus formed. By using sufficient needles so that two needles are left extra on all four sides for closing of the corners and picking these extra stitches from the wales next to the opening on each of the corners, the thumb is inserted with no openings or gaps, as indicated in Figure 4. The thumb is then knitted several courses, narrowed one or more needles on each side and then knitted straight to the specified length.

An edge view of the thumb after insertion is shown at Figure 1. The whole glove is absolutely symmetrical, the two faces being mirror images of each other. It is essential that the symmetry be preserved for proper ambidextrous characteristics. The narrowing of the thumb, at 2 and 3, ensures a proper fit around the thumb, yet leaves sufficient slack so that the thumb is free, and does not cause objectionable looseness.

The ends of the fingers and thumbs may be closed by stitching the loose ends together by hand, using the loose ends of the yarn as a drawstring through the loops, with wooden pegs as darning guides.

By narrowing the thumb near its base on both sides and using a knit construction, the resiliency of the knitting is sufficient to prevent tautness or slack at the base of the thumb on either side.

For a specific example, an excellent knitted glove for Army use may be made by using a three-ply wool yarn for the cuff and a two-ply yarn for the hand and fingers. A medium size glove may be knitted by using 76 needles on a $4\frac{1}{4}$ inch diameter cylinder machine, 32 needles for the thumb, 24 needles for the first, second and third fingers, and 22 needles for the little finger. The number of needles and the size of the yarn may, of course, be varied depending upon the fineness of the yarn and the weight of the glove desired.

For this size glove, 12 stitches are left open at the thumb, as shown in the enlarged detail drawing, Figure 3. The extra stitches at the ends, four at each, then account for the 32 needles. When about 10 courses have been knitted, one needle is dropped at each end of each, leaving 28 needles for the remainder of the thumb.

The number of needles and ply of yarn is given as an example only. The number of needles and ply can be varied over wide limits, to give the weight of finished glove desired. Where a very fine gage knit is desired, the fingers may be knitted with a small slot in the side to which addi-

tional needles may be picked to give greater fullness through the finger portion.

I claim:

- 5 1. A method of knitting gloves comprising knitting from the wrist portion upwards, inserting a loose thread between portions of two adjacent courses where the thumb is desired, while completing the knitting of the palm and back, removing the loose thread, and setting up the loosened loops of said portions on needles, setting additional needles at each end of each portion into adjacent wales, knitting several courses, narrowing both ends of each row of needles, then completing the knitting of the thumb.
  - 10 16. 2. A seamless knit glove of ambidextrous pattern, comprising a palm, said palm having a thumb opening extending through a plurality of wales in a portion of two adjacent courses, and a thumb having at its base a plurality of wales in excess of the number of said first-mentioned wales, said thumb being uniformly narrowed on both faces at a point slightly above its line of attachment to the palm of the glove.
  - 20 25. 3. In a method of knitting gloves, the steps of knitting a wrist portion, then the palm portion to the level of the thumb, knitting in a draw thread between portions of courses in said palm, completing the palm, withdrawing the draw thread, setting up the loosened loops on needles, setting additional needles at each end of each row into additional wales adjacent the loosened loops, then completing the knitting of the thumb.
  - 30 35. 4. The method of claim 3 wherein the fingers are knitted by setting up loose loops on needles, separately for each finger, using additional needles at the side of each finger adjacent an already knitted finger to knit additional wales, whereby gaps in the finger crotch are prevented.
  - 40 45. 5. An ambidextrous seamless knit glove comprising a palm, said palm having a thumb opening extending through a plurality of wales in a portion of two adjacent courses, and a thumb having at its base a plurality of wales in excess of the number of said first-mentioned wales.
  - 45 50. 6. A seamless knit glove of ambidextrous pattern comprising a palm having two symmetrical faces, said palm having a thumb opening between a portion of two adjacent courses in said palm, and a thumb portion having at its base a plurality of wales exceeding the number of open stitches in said open portions of said palm, said thumb portion being narrowed at a point slightly above said base.
